HIS ATTORNEY

UNITED STATES PATENT OFFICE.

JACOB RUBENSTEIN, OF NEW YORK, N. Y., ASSIGNOR TO HOLD TIGHT HAT ADJUSTER, INC., OF NEW YORK, N. Y., A CORPORATION OF NEW YORK.

HAT ADJUSTER AND RETAINER.

Application filed April 23, 1923. Serial No. 635,266.

To all whom it may concern:

Be it known that I, JACOB RUBENSTEIN, a citizen of the United States, and a resident of New York, in the county of Bronx, State 5 of New York, have invented a certain new and useful Hat Adjuster and Retainer; and I do hereby declare the following to be a full, clear, and exact description of the invention, such as will enable others skilled in 10 the art to which it appertains to make and use the same.

My invention relates to hats for women's wear and has particular reference to a means for adjusting the head size of such 15 hats. Women's hats, according to the prevailing style, are made of sufficient size in the crown to enable them to fit well down over the wearer's head. In order that the hats may be worn in this way without the 20 use of fastening or hat pins, it has heretofore been customary to have the hats fit closely in order that they will be retained on the head, as otherwise they would easily become disarranged, or, in the event of its 25 being windy, readily blown off. Because of such necessity of having the hat fit closely on the head, it has been more difficult than formerly to obtain a ready fit. To obviate 30 such difficulty and enable any approximate oversize of hat to be readily and properly fitted to a wearer's head has been the object 35 of my present invention. This object I attain by providing the hat with a flexible strip arranged to extend across the head space in the hat in a position slightly forward of its rear end where it will engage 40 the back of the wearer's head and firmly hold the hat in place.

Referring now to the accompanying 45 drawing forming part of the above specification—

Figure 1 shows a hat equipped with my invention in position on the wearer's head, the holding strip being shown in dotted 50 lines.

Fig. 2 is a bottom view of the hat removed from the wearer's head, and

Fig. 3 is a view of the holding strip detached from the hat.

It will be understood that my invention 55 may be applied to any shape or style of women's hat.

The hat here shown, indicated at 2, is provided with a flexible strip 3 extending across 60 the head space in the hat in a position for-

ward of its rear end 4, which strip is provided at its opposite ends with suitable fastening devices, such as the safety pins 5, for detachable and adjustable connection with the hat. With the strip 3 in this position 60 in the hat, when the latter is placed on the wearer's head, such strip will engage the head at the back thereof, as indicated by dotted lines in Fig. 1, and act to firmly hold the hat in place. By adjusting the position 65 of the strip 3 forward or backward in the hat, it will be obvious that the hat may be readily adjusted or adapted to fit most any size of head. A certain variation of size without adjustment of the ends of the strip 70 may also be provided for by making the strip of elastic material, which I preferably do. When thus made of elastic, the strip will of course yield more or less and so automatically adapt itself to the wearer's head. 75

It is desirable that the elastic strip 3 should be a relatively broad one, as shown, for contact with the wearer's head, and as a means to maintain it flat and prevent twisting of the same, metallic fastening devices 80 7 are provided at the opposite ends of the strip which grip the same throughout its width. These devices 7 not only serve to prevent twisting of the elastic strip, but they also provide loops through which the 85 fastening devices or pins 5 extend for connection with the elastic strip, as clearly shown in Fig. 3.

With the use of the strip 3 in the position 90 shown and described, it will act to always hold the hat, of whatever size it may be, with the front thereof in normal position to the face as the flexibility of this class of 95 hats will assure their ready conformation or fit to the wearer's head at the front thereof under the pulling action of the elastic strip 3 at the rear side of the head. The fact that the hat at its rear end may be slightly spaced from the rear of the wearer's head will be wholly unobjectionable from 100 the standpoint of appearance for the reason that it will not be observable from the rear, and on the other hand, it will be desirable from the standpoint of health and comfort, in that it will prevent the hat from 105 bearing too closely against the rear of the head, a slight air space at such point being desirable in any event.

A further and important feature of the 110 use of the strip 3 as a means for holding the

hat in place, is the fact that its fastening devices 5 may be secured to the lining 6 of the hat as shown and thus avoid marring the exterior appearance of the hat as is done 5 with the use of hat pins.

What I claim is:

A device for holding on a woman's hat comprising in combination with a hat, a relatively wide elastic strip extending across 10 the head space in the hat in a position forward of its rear end, metallic stiffening devices adjacent the ends of the strip gripping the latter throughout its width to prevent

twisting of the same and providing loops at the ends of the strip, said loops extending transversely of the strip, and fastening means for detachably securing the strip within the hat extending through said loops transversely of the strip, said fastening means being substantially confined to the 20 longitudinal plane of said strip and having guarded hat piercing portions.

In testimony whereof I affix my signature:

JACOB RUBENSTEIN.
